UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF DELAWARE

WEB-FEEDING MECHANISM.

Application filed November 9, 1922. Serial No. 599,897.

To all whom it may concern:

Be it known that I, HOWARD M. BARBER, a citizen of the United States, and resident of Stonington, in the county of New London and State of Connecticut, have invented a new and useful Improvement in Web-Feeding Mechanism, of which the following is a specification.

In feeding webs of fabric to cutting mechanisms to be cut into sheets of predetermined lengths, it has been extremely difficult to properly handle loosely woven or light fabrics, and especially burlap, because of the tendency to wrinkle, by reason of the bias weave, tight and loose selvage and the other imperfections that are always present in materials of this nature. Customary means consists in either a feed drum with pressure feed rollers coating therewith or a series of feed rollers around which the fabric web is passed in entering the machine. Either of these means causes the looseness or bias wrinkle in the fabric to accumulate back of the feed rollers, this accumulation being forced or fed through the rollers at intervals, thereby causing quite a variation in the length of sheets cut from the web.

The object of my invention is to provide web feeding means which will entirely overcome this objectionable feature.

My invention comprises a feed drum and a pair of pressure feed rollers normally contacting therewith, means being provided for automatically moving the rollers alternately out of contact with the drum to prevent the formation of the looseness or wrinkle, said means being timed to permit both of the rollers together to be left in contact with the drum for a short period in each cycle of operations so as to ensure the well known feeding of the web at all times.

A practical embodiment of my invention is represented in the accompanying drawings, in which—

Fig. 1 represents in side elevation a portion of a web feeding and cutting mechanism with my invention applied thereto.

Fig. 2 represents a top plan view of the same.

Fig. 3 represents a detail view, showing one period in the cycle of operations with one of the pressure feed rollers contacting with the feed drum.

Fig. 4 represents a similar view, showing another period in the cycle of operations

with both pressure feeding rollers in contact with the drum.

Fig. 5 represents another period in the cycle of operations, showing the other pressure feed roller moved out of contact with the drum.

Fig. 6 represents a similar view, showing both pressure feeding rollers moved out of contact with the drum by the manually operated means.

The web feed drum 1 is mounted on the shaft 2, which shaft is positively driven from the drive shaft 3 through the geared connection 4, 5. A pair of pressure feed rollers are denoted by 6, 7, the swinging supports for the roller 6 being denoted by 8 and the swinging supports for the roller 7 being denoted by 9. These swinging supports 8 and 9 are loosely mounted on a cross shaft 10, located over and in proximity to the feed drum 1. The pressure feed rollers 6 and 7 are positively driven from the shaft 2 of the feed drum, through the gears 11, 12 and 13, except when manually moved out of contact with the web feed drum 1.

The rocking movement of the cross shaft 10 is controlled by a rotary box cam 14, fixed to the shaft 15 which is positively driven from the drive shaft 3 through the train of gears 16, 17, 18, 19. A lever 20 is fixed to the cross shaft 10 and it is provided with a stud or roller 21, located in the cam groove 22 of the cam 14. Arms 23 are fixed to the cross shaft 10, which arms are provided with laterally extended portions 24, 90 arranged in position to engage the swinging supports 8, 9 of the pressure feed rollers 6 and 7, to alternately move the pressure rollers out of contact with the feed drum 1 as the shaft is rocked in one or the other direction, a slight lost motion being provided between the arm and supports so that when the shaft is in an intermediate position, both pressure feed rollers 6 and 7 will be left in contact with the feed drum. Springs 25, 26 are provided, in the present instance for yieldingly holding the pressure feed rollers normally in contact with the drum.

The means which I have shown for manually raising either one or both of the pressure feed rollers out of contact with the feed drum, at pleasure, is constructed, arranged and operated as follows:

The swinging supports 8 and 9 at both ends of the feed rollers are provided with

arms 27, 28, arranged in position to be engaged by the faces of eccentric cams 29, 30, fixed on cross shafts 31, 32, to which cross shafts are also fixed handles 33, 34. Stop pins 35, 36 are provided for limiting the upward movement of the handles 33, 34 and stop pins 37, 38 are provided for limiting the downward movement of the handles, the last named stop pins being arranged to engage projecting arms 39, 40 of the said handles.

It will be understood that the automatic movement of the pressure feed rollers 6 and 7 away from the drum is not sufficient to break their geared driving connection therewith.

From the above description it will be seen that I have provided means whereby the tendency of the fabric web to loosen or wrinkle back of the feed rollers is obviated by the alternate raising of the feed rollers out of contact with the feed drum, permitting the loose portions of the fabric to pass; the well known feeding of the web being undisturbed by the provision whereby both of the pressure feed rollers are left in contact with the drum for a short period in each cycle of operations.

It will also be seen that I have provided manual means whereby either one of the pressure feed rollers, or both together, may be moved out of contact with the feed drum, when so desired.

It will also be seen that by positively driving the pressure feed rollers as well as the feed drum, all tendency of the web to slip is eliminated.

It is evident that various changes may be resorted to in the form, construction and arrangement of the several parts without departing from the spirit and scope of my invention; hence I do not wish to be limited to the particular embodiment herein shown and described, but

45 What I claim is:—

1. Web feeding mechanism comprising, a feed drum, a pair of pressure feed rollers normally contacting therewith, and automatic means for moving the rollers alternately out of contact with the drum.

2. Web feeding mechanism comprising, a feed drum, a pair of pressure feed rollers normally contacting therewith, and automatic means for moving the rollers alternately out of contact with the drum, said means being timed to permit both rollers together to be left in contact with the drum for a short period in each cycle of operations.

3. Web feeding mechanism comprising, a feed drum, a pair of pressure feed rollers normally contacting therewith, automatic means for moving the rollers alternately out of contact with the drum, and manual means for moving either one or both rollers out of contact with the drum, at pleasure.

4. Web feeding mechanism comprising, a feed drum, a pair of pressure feed rollers normally contacting therewith, automatic means for moving the rollers alternately out of contact with the drum, said means being timed to permit both rollers together to be left in contact with the drum for a short period in each cycle of operations, and manual means for moving either one or both rollers out of contact with the drum, at pleasure.

5. Web feeding mechanism comprising, a feed drum, a pair of positively driven pressure feed rollers contacting therewith, and automatic means for moving the rollers alternately out of contact with the drum.

6. Web feed mechanism comprising, a feed drum, a pair of positively driven pressure feed rollers contacting therewith, and automatic means for moving the rollers alternately out of contact with the drum, said means being timed to permit both rollers together to be left in contact with the drum for a short period in each cycle of operations.

7. Web feeding mechanism comprising, a feed drum, a pair of positively driven pressure feed rollers contacting therewith, automatic means for moving the rollers alternately out of contact with the drum, and manual means for moving either one or both rollers out of contact with the drum, at pleasure.

8. Web feeding mechanism comprising, a feed drum, a pair of positively driven pressure feed rollers contacting therewith, automatic means for moving the rollers alternately out of contact with the drum, said means being timed to permit both rollers together to be left in contact with the drum for a short period in each cycle of operations, and manual means for moving either one or both rollers out of contact with the drum, at pleasure.

9. Web feeding mechanism comprising, a feed drum, a pair of pressure feed rollers normally contacting therewith, geared connections between the drum and rollers, and automatic means for moving the rollers alternately out of contact with the drum without breaking their geared connection therewith.

10. Web feeding mechanism comprising, a feed drum, a pair of pressure feed rollers normally contacting therewith, geared connections between the drum and rollers, and automatic means for moving the rollers alternately out of contact with the drum without breaking their geared connection therewith, said means being timed to permit both rollers together to be left in contact with the drum for a short period in each cycle of operations.

11. Web feeding mechanism comprising, a feed drum, a pair of pressure feed rollers

normally contacting therewith, geared connections between the drum and rollers, automatic means for moving the rollers alternately out of contact with the drum without 5 breaking their geared connection therewith, and manual means for moving either one or both rollers out of contact with the drum, at pleasure.

12. Web feeding mechanism comprising, 10 a feed drum, a pair of pressure feed rollers normally contacting therewith, geared connections between the drum and rollers, automatic means for moving the rollers alternately out of contact with the drum without 15 breaking their geared connection therewith, said means being timed to permit both rollers together to be left in contact with the drum for a short period in each cycle of operations, and manual means for moving either one or both rollers 20 out of contact with the drum, at pleasure.

13. Web feeding mechanism comprising, a feed drum, a pair of pressure feed rollers normally contacting therewith, a cross shaft, 25 swinging supports for the feed rollers loosely mounted on said shaft, cam controlled means for rocking the shaft, and an element carried by said shaft in position to engage said feed roller supports for alternately 30 moving the rollers out of contact with the drum.

14. Web feeding mechanism comprising, a feed drum, a pair of pressure feed rollers normally contacting therewith, a cross shaft, 35 swinging supports for the feed rollers loosely mounted on said shaft, cam controlled means for rocking the shaft, and an element carried by said shaft in position to engage said feed roller supports for alternately 40 moving the rollers out of contact with the drum, the cam controlled means being timed to permit both rollers together to be left in contact with the drum for a short period in each cycle of operations.

15. Web feeding mechanism comprising, 45 a feed drum, a pair of pressure feed rollers normally contacting therewith, a cross shaft, swinging supports for the feed rollers loosely mounted on said shaft, cam controlled 50 means for rocking the shaft, an element carried by said shaft in position to engage said feed roller supports for alternately moving the rollers out of contact with the drum, and manual means for moving either 55 one or both rollers out of contact with the drum, at pleasure.

16. Web feeding mechanism comprising, a feed drum, a pair of pressure feed rollers normally contacting therewith, a cross shaft, swinging supports for the feed rollers loosely mounted on said shaft, cam controlled

means for rocking the shaft, an element carried by said shaft in position to engage said feed roller supports for alternately moving the rollers out of contact with the drum, the cam controlled means being timed to permit both rollers together to be left in contact with the drum for a short period in each cycle of operations, and manual means for moving either one or both rollers out of contact with the drum, at pleasure.

17. Web feeding mechanism comprising, a feed drum, a pair of positively driven pressure feed rollers normally contacting therewith, a cross shaft, swinging supports 75 for the feed rollers loosely mounted on said shaft, a cam controlled lever for rocking said shaft, an element carried by said shaft in position to engage said feed roller supports for alternately moving the rollers out of contact with the drum, the movement of the cam controlled lever being timed to permit both rollers together to be left in contact with the drum for a short period in each cycle of operations, and a pair of 80 cam levers arranged to be manually operated for moving either one or both rollers out of contact with the feed drum, at pleasure.

18. Web feeding mechanism comprising, 90 a feed drum, a pair of rollers normally contacting therewith, and automatic means for alternately moving each feed roller out of contact with the feed drum, at intervals.

19. Web feeding mechanism comprising, 95 a feed drum, a pair of rollers normally contacting therewith, and automatic means for alternately moving each feed roller out of contact with the feed drum, at intervals, said means being timed to permit the feed 100 rollers to be left in contact with the drum for a short period, at intervals.

20. Web feeding mechanism comprising, a feed drum, pressure feed rollers normally contacting therewith, means for moving 105 each feed roller out of contact with the feed drum, at intervals, and manual means for moving each feed roller out of contact with said drum, at pleasure.

21. A feed drum, pressure feed rollers normally contacting therewith, means for moving each feed roller out of contact with the feed drum, at intervals, said means being timed to permit the said feed rollers to be left in contact with the drum for a 110 short period, at intervals, and manual means for moving each feed roller out of contact with said drum, at pleasure.

In testimony, that I claim the foregoing as my invention, I have signed my name 120 this 2d day of November A. D. 1922.

HOWARD M. BAREER.
